Hiram Holcot, Stow, Massachusetts.

Letters Patent.

The Schedule, referred to in these Letters Patent, and making part of the same, containing a description in the words of the said Hiram Holcot, himself of his improvement in the Manufacture of Cloth.

To all to whom these presents shall come.

Be it known that I Hiram Holcot of Stow in the County of Middlesex State of Massachusetts, Mechanist, have invented a new and useful improvement in the Manufacture of Cloth & that the following is a full description of the invention. Let a sheet of thin brass plate about five inches wide be rolled until it shall acquire a proper temper & elasticity then let the same be cut into strips equal in length to the width of such cylinders as are now used for napping cloth with teazles, then let the said plate be divided lengthwise so that the inner edges shall present a row of teeth about three quarters of an inch in length & about one fifteenth of an inch wide at the base diminishing in width from the base to the tip where they terminate in a sharp point, then let a considerable curvature begin to the beginning, that is by placing the plate thus cut over a massive iron mould so fashioned as to give the teeth of the plate a proper curvature and then placing a corresponding convex iron over them and giving it a blow with a hammer. The metallic upper will then be complete and will be a plate with a row of curved tapering elastic teeth resembling the teeth of the teazle, and standing out from the smooth part of the plate at such an angle that the smooth part may be attached to slats of wood napping across the face of a cylinder at suitable distances. The teeth are cut by the oblique strokes of a chisel the direction of which is changed each stroke as described in plan marked A. here to succeed. The two sides of the plate are then drawn apart separating at the points of the teeth by two plates as the separated from one with a row of teeth on one side

side of cloth, the following arrangement of parts forming the
clothes to be desped. The article consists of a frame with a base
B, hereto annexed. The invention for which I for the use of which
the said Hobart claims his patent is for making from a sheet
of thin lead a plate with inward tapering elastic teeth suitable
for napping cloth. And the great merit of the invention is the
production of an elastic and enduring article which may be
substituted to an almost inextinguishable extent for the old
teazel which is destroyed by a few hours use.
